UNITED STATES PATENT OFFICE.

EUGENE BRETNAY AND JOHN T. DICKSON, OF INDIANAPOLIS, INDIANA.

GAS-GENERATOR.

SPECIFICATION forming part of Letters Patent No. 552,095, dated December 31, 1895.

Application filed January 12, 1892. Serial No. 417,877. (No model.)

To all whom it may concern:

Be it known that we, EUGENE BRETNAY and JOHN T. DICKSON, citizens of the United States, residing at Indianapolis, in the county 5 of Marion and State of Indiana, have invented certain new and useful Improvements in Gas-Generators, of which the following is a specification.

Our said invention relates to that portion of 10 an ice-making, refrigerating or such like apparatus known as the "generator" or "retort," wherein the ammonia or equivalent gas is expelled from the aqua-ammonia by the action of heat, and rectified before passing to the 15 condenser. It consists in a novel construction of the steam-heating apparatus whereby greatly-increased efficiency is attained and at the same time a less expensive apparatus than that commonly in use is provided, all as 20 will be hereinafter more particularly described and claimed.

Referring to the accompanying drawings, which are made a part hereof, and on which similar letters of reference indicate similar 25 parts, Figure 1 is a central vertical section through the generator, the heater being shown in elevation; Fig. 2, a similar view through the heater, the central portion being broken away to permit the ends to be represented on 30 an enlarged scale; and Fig. 3, a horizontal section as seen when looking in the direction indicated by the arrows from the dotted line 3 3 in Fig. 1.

In said drawings the portions marked A 35 represent the casing of the generator, B a system of pans arranged in the upper portion thereof for retarding the inflow of the aqua-ammonia, and C the steam-heater.

The casing A of the generator is preferably 40 of uniform size and shape throughout its height. Its top is dome-shaped having a pipe A' jointed to the apex thereof, through which the gas is afforded an outlet and conducted to the condenser. A pipe A², through which 45 the aqua-ammonia is conducted to the generator, is also inserted through said top to discharge therein, and a pipe A³ with a regulating-valve a³ is provided near the bottom of the casing for the outlet of the weak liquor.

50 The pans B are of a common construction and arrangement, consisting of alternately-arranged large and small pans supported in

a casing by appropriate supports, such as bolts a, from a cross-bar a', as shown, the aqua-ammonia being discharged upon the top 55 of said casing, and runs into the top pan through perforations therein, being discharged into the next pan through a central perforation in the top pan, and into the next large pan by running over the edges of the 60 small pan, and so on until it reaches the perforated bottom of the casing through which the liquor runs into the lower portion of the generator surrounding the steam-heater. A ring a² is provided at the top of the casing, 65 within which the pans are inclosed, of sufficient width to close the space between said casing and the main casing of the generator, as shown, thus insuring that all the liquor shall pass through this retarding apparatus. 70

The steam-heater C to which our invention particularly relates consists of a central vertical pipe or cylinder provided with numerous radial hollow arms c, arranged in staggered vertical lines, the inner ends of which project 75 through said cylinder a short distance, for a purpose which will be presently described. Each end of said pipe or cylinder is preferably formed screw-threaded, and has a collar C' screwed thereon. A cap C² is firmly secured thereto by means of bolts c', a packing-ring c² being interposed between said collar and said cap to secure a steam-tight joint. The end of the cap on the lower end of said 80 heater is mounted in a step a⁴ on the bottom 85 of the casing A, and the upper cap may be provided with an eye c⁵, by which the heater may be conveniently connected to lifting mechanism for handling. The steam enters 90 said heater through the inlet-pipe C³, which is provided with a regulating-valve c³, and the products of condensation are discharged through the outlet-pipe C⁴, which is also provided with a regulating-valve c⁴. The several joints are securely packed by nuts and 95 packing-rings, as shown, to render them steam and gas tight. The joints between the radial arms c and cylinder C are made by the parts being screwed and nicely fitted together. The pipe C³ being secured to the top of the 100 heater and casing A serves to steady said heater in position, as also does the pipe C⁴.

Heretofore steam-coils have commonly been employed as the heating apparatus in genera-

tors of this class. In such apparatus the condensation forms in the pipe ahead of the steam and thus covers the pipe-surface and reduces the degree of heat transmitted to the 5 surrounding chamber, inasmuch as in a large portion of the coils the heat of hot water alone is secured. A very high pressure and temperature of steam is thus required to accomplish the desired result, and a great per 10 cent. of heat is lost, and the apparatus fails to reach its possible capacity. Such a temperature, as is well known, is also calculated to give to the products of condensation or distilled water, of which the ice is made, a 15 disagreeable or bitter taste. It is therefore desirable to secure the greatest possible capacity for the apparatus at the lowest possible temperature of the steam, and this result we believe we have accomplished by the 20 above-described apparatus. In said apparatus the steam comes into the heater through the pipe C³ under the desired pressure, filling said heater throughout all its parts, including the radial arms, the desired pressure therein 25 being secured and maintained by a proper adjustment of the valves c³ and c⁴. By reason of receiving the steam at the top the products of condensation fall to the bottom of their own gravity, the condensation in the radial 30 arms being conducted to within the central cylinder by the inwardly-extended ends of said arms to a point where it will fall directly to the bottom without touching the sides of said cylinder. By this construction live steam 35 is maintained constantly against the sides of said cylinder and substantially the entire surface of the radial arms, and thus the heat of live steam is constantly transmitted to the outside chamber throughout substantially the 40 entire surface of the heater, which, as will be readily understood, enables a greater temperature to be secured in said chamber, and a greater capacity is thus given the machine, while at the same time a lower temperature 45 of steam can be maintained, which secures a more desirable quality of distilled water to be made into ice.

Other than as above described the operation of the generator is the same as that of generators in common use, the aqua-ammonia being introduced through the pipe A² and distributed through the apparatus B into the chamber

surrounding the heater, when the staggered arrangement of the arms c causes it to be still further broken up and disturbed in its course, 55 thus bringing a greater per cent. of it into direct contact with the heating-surface. The heat causes the ammonia-gas to be ejected from the aqua-ammonia. Said gas arises and passes upwardly through the downwardly-flowing aqua-ammonia, being rectified, and passes out through the pipe A' to the condenser. (Not shown.) The weak liquor from the bottom of the generator passes out through the pipe A³ to the equalizer, the weak-liquor 60 tank, and absorber, where it is reunited with the gas, and again comes back to the generator through the pipe A², all as is well known and understood. This invention being confined entirely to the generator, the other portions 65 of the apparatus have not been shown, as the use of the generator in connection with said other portions of the apparatus is well known and understood.

Having thus fully described our said invention, what we claim as new, and desire to secure by Letters Patent, is—

1. In a gas generator, the combination of the casing, the inflow pipe for the liquor, the outflow pipes, and the heater, said heater consisting of a vertical chamber provided with numerous radial hollow arms the inner ends of which arms project a short distance within said chamber, whereby the drippings therefrom will fall directly to the bottom of said 85 chamber without running down its sides, substantially as set forth.

2. In a heater for use in a gas generator, the combination of the cylinder C provided with a collar C' secured on each end, a perforated 90 cap C² secured to each collar by clamping bolts, a packing ring c² interposed between said collar and said cap, the radial arms c connected with said cylinder, and suitable inlet and outlet pipes, substantially as set forth. 95

In witness whereof we have hereunto set our hands and seals, at Indianapolis, Indiana, this 7th day of January, 1892.
